UNITED STATES PATENT OFFICE.

CARL C. KUSTERER, OF GRAND RAPIDS, MICHIGAN.

CONCEALED HINGE FOR COACH-DOORS.

1,083,622.

Specification of Letters Patent.

Patented Jan. 6, 1914.

Application filed May 14, 1912. Serial No. 697,107.

To all whom it may concern:

Be it known that I, CARL C. KUSTERER, a citizen of the United States, residing at Grand Rapids, Michigan, have invented certain new and useful Improvements in Concealed Hinges for Coach-Doors, of which the following is a specification.

This invention relates to improvements in concealed hinges for coach doors.

10 The objects of this invention are:

First, to provide an effectively adjustable hinge to accommodate the angle and curve and inequalities of post and door, also in accuracies of construction of the bodies of 15 such vehicles. I also provide flexibility due to limited movement on account of oversize of screw holes of hinge plate accomplishing self alinement of two or more pintles on same door.

20 Second, to provide an improved construction in which the hinge is readily detachable without the breaking of fitted joints.

Third, to provide an improved hinge in which lost motion is obviated when the door 25 is in closed position and the strain relieved on the pin during the swing of the hinge and when it is in the open position.

Fourth, to provide a hinge in which the parts of any one are interchangeable with 30 those of any other, an obvious advantage as this permits the pillar-post-housing to be applied to the casing in the body department and the hinge member to the doors in the door department of a manufactory.

35 Fifth, to provide a pillar-post-housing which may be applied reversibly and used on right or left hand doors at convenience.

Sixth, to provide a pillar-post-housing in combination with the pillar of such form 40 that the pillar need be only notched to receive it as distinguished from mortised.

Further objects, and objects relating to details and economies of construction will definitely appear from the description to 45 follow.

I accomplish the objects of my invention by the devices and means described in the following specification.

The invention is clearly defined and pointed out in the claims.

Structures which are preferred embodiments of my invention are fully illustrated in the accompanying drawing, forming a part of this specification, in which:

55 Figure I is a detail perspective view of the preferred form of my hinge in place, cou-

pling the door to the pillar. Fig. II is a detail perspective view of the detached hinge separated from both the pillar plate and the door. Fig. III is a detail perspective view 60 of pillar plate to which the hinge is detachably attached. Fig. IV is a detail transverse sectional view through the hinge illustrated in Fig. I, showing in dotted lines the location of the door when open. Fig. V is a detail vertical sectional view on a line through the attaching screws of the upper part of Fig. I. Fig. VI is a detail view of a modification, showing the tapped holes 23 for the retaining screws for the hinge plate and a sheet metal wall for the housing. Fig. VII is a detail elevation view of one of my 70 hinges in place with the door open, looking toward the pillar plate and illustrating the wedging part 18 of the hinge arm 14. Fig. VIII is a transverse detail sectional view 75 similar to that appearing in Fig. IV, of a modified form and shows detail construction enabling the sheet metal forming the outside surface of the body to be turned inward to avoid raw edge of metal and give a flush finish on the pillar, taken on a line corresponding to line 8—8 of Figs. VII and IX. Fig. IX is a detail vertical sectional view 80 through a modified form, which has preference for certain grades and kinds of bodies wherein the pillar plate and housing is of sheet metal stamping, taken on line 9—9 of Fig. VIII. Fig. X is a detail transverse sectional view through the pillar plate 85 and housing, as modified when made entirely of sheet metal, taken on a line corresponding to line 8—8 of Fig. IX. Fig. XI is a detail perspective view of the modification shown in Fig. X.

In the drawing, similar numerals of reference refer to similar parts throughout the several views, and the sectional views are taken looking in the direction of the little arrows at the ends of the section lines.

Referring to the numbered parts of the drawing, a pillar 1 is usually finished on the exterior with a plate of aluminum or other metal 2, with a suitable molding 2' around the edge of the same. The door 3 is of any required form and is supported by the hinges.

A fixed pillar plate 4, having a housing 5, preferably integral therewith, is let into the pillar by a corresponding notch to receive 110 the hinge arms and is retained in place by suitable screws, as 6. A seat 7 is formed on

this pillar plate, which is preferably shouldered as at 11—11 for that purpose, and is provided with screw holes 10, 10',—see Fig. III. The detachable hinge plate 8 loosely fits this seat 7, and screws 9 extend through the same and through the holes 10 into the wood, as shown in Fig. V in one construction. Because of the loose fit of the hinge plate 8, the parts are effectively but inconspicuously adjustable to take care of inequalities in the bodies, particularly when the bodies are curved bodies. The screws are tapped into the pillar plate in another construction, as appears at 23 in Fig. VI, where the housing 22 is of sheet metal. Each form meets special requirements.

On the detachable hinge plate 8 are hinge arms 16, which extend into the housing 5 and through which is disposed the hinge pin 15. The opposite hinge member 12 is let into the door 3 being secured by screws 13, and is provided with an outwardly curved hinge arm 14 which extends into the housing, and at its outer end, the pin 15 hinges the same to the arms 16. Owing to the curvature of this arm, it permits the door 3 to swing outwardly.

The arm 14 is slightly beveled at 18 and fits with a sliding fit into the aperture 17 in the plate 8, so that when the door is swung on its hinges, the hinge fits snugly and relieves strain on the hinge pin. The wedge-shaped portion 18 strikes the sides of the aperture 17 when the door closes and wedges tight and avoids all play.

Stops 18' are provided and disposed toward the outer side of the hinge plate 8 against which the hinge member 14 strikes to limit the movement of the same and prevent the door striking against the outside of the pillar or body. Where the sheet metal exterior 2 is conformed around the pillar, the structure is modified as clearly appears in Fig. VIII. A longitudinal groove is here cut in the face of the frame-like plate at its outer edge, into which the sheet-like body covering is extended and secured, the relation fully appearing by considering Fig. XI in this connection. This modified form without the longitudinal groove also appears in Fig. VII, where sheet metal 2 is soldered or welded to the housing wall. In another construction, this pillar plate and housing is formed of a stamping 24 having extensions 24', in which the shoulders 11 are eliminated and the plate 8 is screwed directly to the seat on the outside of this pillar plate, as clearly appears in Fig. IX. The contour of the stamping appears in cross section in Fig. VIII. By shaping the wall thus, the hinges are interchangeable, either rights or lefts.

In Figs. X and XI, I show the pillar plate and housing entirely of sheet metal, which may be either a simple stamping, or

may be made with riveted, or soldered, or welded joints. I show the same conventionally. The ends 29 are extended to form the seat for the hinge plate. The edges are outwarded at 29' to form a shoulder and the housing 27, corresponding to the housing 5 of the main structure, is extended at 28 to afford a continuous connection to the outer plate 2, which is preferably welded or soldered thereto. From this description, it is clear that the structure can be modified without departing from my invention. The integral construction of the pillar plate and housing is preferred, but I have shown how the same can be made up of parts to serve the purpose very effectively, and on cheap work, the housing wall may be omitted.

The plate 8 loosely fits in the seat 7 of the pillar plate and it is thus possible, after designing a body, to apply this hinge and thereafter drill the holes for the screws so that the door may thereafter be readily detached without removing the pillar plate from the woodwork and no permanent joint is broken. This is best accomplished by applying one of a pair of hinges complete and drilling the screw holes in the seat of the other when placed.

The screw holes are made a trifle larger than the screws. This gives a flexibility to the attachment of the hinge, which is highly desirable, and with the loose fit of the hinge plate, assures the most perfect alinement of the hinges which, at the same time, are securely clamped in place.

Because it is not necessary to break the joint, the material of the body is always protected against moisture and the doors can be readily removed during the finishing process, or for any other reason, and will, as they fit a metal pillar plate, always go back to place without perceptible wear.

In Figs. VII, VIII and IX, I illustrate the housing 24, corresponding to the housing 5, formed of sheet metal, with extension 24' to form a seat for the hinge plate, and provide a frame-like plate 26 to receive an inset hinge plate 25. By this means, a shouldered seat is provided that is completely adjustable to accommodate the hinge plate, insuring that when the structure is once perfectly adjusted, it can in no way get out of line when it is disassembled and reassembled.

Having thus described my invention, what I claim as new and desire to secure by Letters Patent is:

1. In a hinge structure, the combination of a fixed pillar plate with a suitable housing and a seat for the hinge plate, an adjustable hinge member comprising an apertured plate with inwardly projecting pivot carrying arms adapted to loosely fit the said seat and housing, means for retaining the same in place, a hinge member for the door

- with an outwardly projecting hinge arm curved to clear the edge of the pillar disposed within the housing of said pillar plate, the said arm being beveled to wedge 5 into the aperture of the hinge plate, coacting for the purpose specified.
2. In a hinge structure, the combination of a fixed pillar plate with a suitable seat for the hinge plate, an adjustable hinge 10 member comprising an apertured plate with inwardly projecting pivot carrying arms adapted to loosely fit the said seat, means for retaining the same in place, and a hinge member for the door with an outwardly 15 projecting hinge arm curved to clear the edge of the pillar disposed within the said pillar plate, the said arm being beveled to wedge into the aperture of the hinge plate, coacting for the purpose specified.
- 20 3. In a hinge structure, the combination of a fixed pillar plate with a suitable seat for the hinge plate, an adjustable hinge member comprising an apertured plate with inwardly projecting pivot carrying arms 25 adapted to loosely fit the said seat, means for retaining the same in place, and a hinge member for the door with an outwardly projecting hinge arm curved to clear the edge of the pillar disposed within the said 30 pillar plate, coacting for the purpose specified.
4. In a hinge structure, the combination of a fixed pillar plate with a suitable housing and a seat for the hinge plate, an adjustable hinge member comprising an apertured plate with inwardly projecting pivot 35
- carrying arms adapted to loosely fit the said seat and housing, means for retaining the same in place, and a hinge member for the door with an outwardly projecting hinge arm curved to clear the edge of the pillar disposed within the housing of said pillar plate, coacting for the purpose specified. 40
5. In a hinge structure, a pillar plate and housing formed of sheet metal with extensions forming a seat, the edges of which are up-turned and alined with an extension of said housing and adapted to be united with the body metal, as specified. 45
6. In a hinge structure, the combination of a pillar plate with a suitable hinge plate seat, an adjustable frame-like plate and means for securing the same to the said seat, a hinge plate conformed to the said frame-like plate, and means for securing the 50 same in place.
7. In a hinge structure, the combination of a pillar with a plate seat formed therein, a frame-like pillar plate with a longitudinal groove on its face at its outer edge, means for securing said frame-like plate in place, 55 a sheet-metal body covering, the folded edge of which conforms to said groove, a hinge plate conformed to the frame-like plate, and means for securing the same in place. 60
- 65 In witness whereof, I have hereunto set my hand and seal in the presence of two witnesses.
